George W. Look, ^{inventor}
By Charles Turner Brown,
Attorney

UNITED STATES PATENT OFFICE.

GEORGE W. LOOK, OF QUINCY, MINNESOTA.

AERATOR FOR MILK.

SPECIFICATION forming part of Letters Patent No. 695,570, dated March 18, 1902.

Application filed January 10, 1902. Serial No. 89,111. (No model.)

To all whom it may concern:

Be it known that I, GEORGE W. LOOK, a citizen of the United States, and a resident of Quincy, county of Olmsted, and State of Minnesota, have invented certain new and useful Improvements in Aerators for Milk, of which the following, when taken in connection with the drawing accompanying and forming a part hereof, is a full and complete description, sufficient to enable those skilled in the art to which it pertains to understand, make, and use the same.

This invention relates to an apparatus for forcing cooled air through a body of milk, thereby aerating and cooling the milk.

The object of this invention is to obtain an apparatus for cooling air and for forcing the same through a body of milk—as, say, a can of milk—which will be simple in construction and not liable to get out of order.

In the drawing referred to there is shown a vertical view of an apparatus embodying this invention, an elevation of a can containing milk, and a connecting-pipe from the apparatus to the can, the front wall of the can being partially broken away to expose to view the contents of the can, including the lower end of the connecting-pipe, such lower end being shown in vertical section.

A reference-letter applied to designate a given part is used to indicate such part throughout the drawing.

A is an outer receptacle, which may contain water or a mixture of water and ice, water and salt, or other cooling liquid.

B is a receptacle setting into receptacle A.

C is a cylindrical partition in receptacle B and may be attached to the bottom *b* of such receptacle B.

b' is an aperture in the bottom *b* of the receptacle B.

D is a receptacle setting in receptacle B.

E is a cylinder rigidly secured in the neck of the receptacle B, and E' is a packing-box at the upper end of the cylinder E and between such cylinder E and the longitudinally movable cylinder F.

G is a valve in the top of cylinder F outwardly to admit air to such cylinder F when the cylinder is moving upward and closing to prevent the flow of air therethrough when such cylinder F is moved downwardly.

H is the handle, by means of which the cylinder F can be operated.

I is the upper surface of the liquid in receptacle B and in the annular chamber J' between cylinder D and cylindrical partition C of receptacle B.

J is the annular chamber between cylinders E and F and the receptacle D.

K is the outlet from cylinder B, and L is a valve at the upper end of such outlet K.

M is a removable top to the outlet K, and N is a flexible pipe from outlet K to near the bottom of the receptacle O.

P is liquid, as milk, in receptacle O.

Q is a pipe having the flaring lower end *q*, such pipe having the pipe N attached thereto at the upper end thereof, as is shown in the drawing.

When water or other cooling liquid is placed in the receptacle A and receptacle B is then placed in such receptacle A, such cooling liquid may and will flow through aperture *b'* in bottom *b* of such receptacle B, filling or partially filling the annular space in receptacle B between cylindrical partition C and receptacle D.

The apparatus is operated as follows: Cylinder F is moved up and down repeatedly, and air is thereby intermittently drawn into the cylinder through the valve G and forced from such cylinder through annular chamber J, annular chamber J', and outlet K, through valve L, connection M, pipe Q, flaring end *q*, and through the milk P (which is cooled and aerated thereby) in the receptacle O. The packing E' prevents the escape of the air, which is forced through the milk P, as last above described, in the ordinary way of preventing the escape of air around a moving piston by packing.

The air is cooled in its passage through the apparatus by the liquid in receptacle A and in the annular chamber between cylindrical partition C and the receptacle D.

Having thus described my invention, what I claim as new, and desire to secure by Letters Patent, is—

1. In an aerator and milk-cooler, the combination of a receptacle, a cylindrical partition in the receptacle, an additional receptacle fitting loosely in the cylindrical partition of the first-named receptacle, a longitudi-

nally-movable cylinder, a valve in the upper end of the cylinder, an outlet to the first-named receptacle, a check-valve in such outlet, and a flexible connection from such outlet, and an outer receptacle in which the first-named receptacle may be placed, such outer receptacle arranged to hold a cooling liquid, whereby air may be cooled and forced through such flexible connection and through the liquid in which the end of the connection is immersed: substantially as described.

2. In an aerator and milk-cooler, the combination of a receptacle, a cylindrical partition in the receptacle, an aperture in the bottom of the receptacle opening into the chamber within the cylindrical partition, an additional receptacle within the cylindrical partition, whereby cooling liquid surrounding the first-named receptacle may enter the bottom thereof and surround the last-named and inner receptacle, a longitudinally-movable cylinder in the receptacle, such cylinder closed at its upper end, a valve in the upper end of

the cylinder opening on the upward movement thereof to admit air into such cylinder and to close on the downward movement of such cylinder, an outlet from the receptacle, a check-valve in the outlet, a flexible pipe connected with the outlet, and a packing interposed between the neck of the first-named receptacle and the longitudinally-movable cylinder; and an outer receptacle in which the first-named cylinder may be placed, such outer receptacle arranged to hold a cooling liquid; whereby air may be cooled in the apparatus and such air then forced through the outlet thereof and through the flexible connection attached thereto: substantially as described.

Signed at St. Charles, in the county of Winona and State of Minnesota, this 2d day of January, 1902.

GEORGE W. LOOK.

In presence of—

GEORGE PFEFFERKORN,
CHAS. F. KNAPP.
